UNITED STATES PATENT OFFICE.

LAUREN E. CRANE AND THERON H. BLY, OF MINNEAPOLIS, MINNESOTA.

SMOKE-EJECTOR.

No. 827,789.

Specification of Letters Patent.

Patented Aug. 7, 1906.

Application filed August 30, 1905. Serial No. 276,437.

To all whom it may concern:

Be it known that we, LAUREN E. CRANE and THERON H. BLY, citizens of the United States, residing at Minneapolis, in the county 5 of Hennepin and State of Minnesota, have invented certain new and useful Improvements in Smoke-Ejectors; and we do hereby declare the following to be a full, clear, and exact description of the invention, such as will enable 10 others skilled in the art to which it appertains to make and use the same.

Our invention has for its object to provide an improved apparatus for ejecting smoke or fumes by impulses and preferably in the form 15 of rings; and it consists of the novel devices and combinations hereinafter described, and defined in the claims.

The apparatus is adapted to take different forms and is adapted for a great many different uses. For instance, it is especially well adapted for diffusing disinfecting, germ and insect destroying smoke and fumes, and it is also adapted for use as a toy or advertising medium for shooting smoke rings into the 25 air, all as will be hereinafter more fully described.

The invention is illustrated in the accompanying drawings, wherein like characters indicate like parts throughout the several 30 views.

Figure 1 is a view in side elevation, showing the improved apparatus in the form of a cannon. Fig. 2 is a vertical section taken centrally through the apparatus shown in 35 Fig. 1 from front to rear thereof, and Fig. 3 is an enlarged transverse vertical section taken through the device on the line $x^3 x^3$ of Fig. 2.

Referring first to the construction illustrated in Figs. 1, 2, and 3, the numeral 1 indicates the barrel of the toy cannon, the same being rigidly supported by a box-like base 2. The numeral 3 indicates a drawer-like fire-box which is removably fitted into a compartment 4 in the upper forward portion of 45 the base 2. This fire-box is provided with a perforated false bottom 5, below which is an air-inlet duct 6. The compartment 4 opens into the barrel 1 through a plurality of perforations 7, as best shown in Fig. 2. These 50 passages 7 permit the smoke from the burning material 2, contained within the fire-box 3, to pass upward into the intermediate portion of the barrel 1. The extreme outer end of the barrel 1 is provided with a contracted discharge-passage 8. In the rear portion of the barrel 1, at the rear of all the

perforations 7, is a yielding diaphragm 9, preferably constructed of thin spring metal and secured to the barrel only at its upper portion, so that its lower portion is free to vibrate. In the barrel 1, slightly rearward of the diaphragm 9, is a crescent-shaped flange 10, which is secured to the lower portion of said barrel. The flange 10 cuts off the direct passage of air between the barrel and the 65 loose portion of the diaphragm 9.

Mounted on a frame 12, secured within the base 2, is a spring-motor, (indicated as an entirety by the numeral 13.) This spring-motor may be of the usual or any suitable construction, but is arranged to impart rotary motion to a wheel or disk 14, which has a plurality of laterally-projecting circumferentially-spaced cam-pins 15. Mounted in the upper portion of the frame 12 is a short rock-shaft 16, which carries an upwardly-projecting hammer 17 and a depending trip-arm 18. The hammer 17 projects upward through the perforation 11 of the barrel 1, and its head stands in position to strike against the diaphragm 9, approximately at its center. A spring 19, attached to the hammer 17 and to the frame 12, tends to force the head of the hammer against the said disk. The lower end of the trip-arm 18 stands in position to 70 be engaged in succession by the cam-pins 15 of the motor-driven wheel 14. As shown, the spring of the motor 13 is adapted to be wound in the usual way or after the manner of an ordinary clock-spring by means of a 75 key 20.

As is evident, when the spring-motor is thrown into action and the wheel 14 is rotated the cam-pins 15 coming into engagement with a trip-arm 18 will force the hammer 17 away from the diaphragm 9 and then upon passing out of engagement with said arm will release the hammer and permit the head thereof to be thrown against the diaphragm by the spring 19. In this way the 80 diaphragm will be vibrated with sudden impulses and for each impulse will eject from the barrel 1, through the contracted nozzle-passage 8, a puff of smoke which, as has been found in practice, will take the form of a 85 smoke ring. It has also been found in practice that for each time the diaphragm 9 is struck by the hammer it will make two, and sometimes three, vibrations, thereby frequently ejecting two and three smoke-rings in 90 very rapid succession. When this toy cannon is thus put into action and caused to 95

shoot out smoke puffs in rapid succession, it produces a very good imitation of the actual operation of a rapid-fire cannon or gun. Hence this device is adapted for use as a toy and for advertising purposes. For such purposes any suitable smoke-producing material, such as punk or tobacco, may be used. In fact, tobacco-smoke may be blown from the mouth of the smoker into the barrel of the cannon, if desired.

When the apparatus is used for disinfecting purposes, a suitable germ-destroying smoke or vapor should of course be employed and when used to kill insects, such as mosquitos, an insect-destroying material should be burned and ejected from the apparatus.

What we claim, and desire to secure by Letters Patent of the United States, is as follows:

20 1. An apparatus of the kind described, comprising a barrel and a hollow base having the general appearance of a cannon, of a diaphragm within said barrel, a hammer for striking said diaphragm, mechanism located within said base for actuating said hammer, and means for producing smoke within said barrel, substantially as described.

25 2. In an apparatus of the kind described, the combination with a barrel and a hollow

base having the general appearance of a cannon, of a vertically-disposed diaphragm within said barrel attached thereto at its upper portion only, a hammer arranged to strike said diaphragm, mechanism within said base for operating said hammer, and a fire-box 35 also within said base, said barrel having smoke-passages permitting the smoke to pass from said fire-box into the interior of said barrel in front of said diaphragm, substantially as described.

3. In an apparatus of the kind described, the combination with a barrel and means for producing smoke therein, of a resilient diaphragm yieldingly supported in an intermediate position within said barrel, and a hammer arranged to strike said diaphragm and to instantly recede therefrom, whereby said diaphragm will make several vibrations, when struck, and will cause several smoke puffs to be ejected from said barrel, substantially as 45 described.

In testimony whereof we affix our signatures in presence of two witnesses.

LAUREN E. CRANE.
THERON H. BLY.
